US00D939348S

(12) **United States Design Patent** (10) Patent No.: **US D939,348 S**
(45) Date of Patent: ** *Dec. 28, 2021

(54) **CANDLE TUMBLER LID**

(71) Applicant: **The Yankee Candle Company, Inc.**,
South Deerfield, MA (US)

(72) Inventors: **Savannah Walters**, Kalamazoo, MI
(US); **Daniel Lipson**, Northampton,
MA (US); **Jill Buckley**, Mattawan, MI
(US); **Alfredo Carreno**, Portage, MI
(US); **Mark Zavada**, Kalamazoo, MI
(US)

(73) Assignee: **The Yankee Candle Company, Inc.**,
South Deerfield, MA (US)

(*) Notice: This patent is subject to a terminal disclaimer.

(**) Term: **15 Years**

(21) Appl. No.: **29/717,933**

(22) Filed: **Dec. 19, 2019**

(51) LOC (13) Cl. **09-07**
